HARMAN A. M. HARRIS, OF PHILADELPHIA, PENNSYLVANIA.

Letters Patent No. 69,092, dated September 24, 1867.

IMPROVEMENT IN PUMPS.

The Schedule referred to in these Letters Patent and making part of the same.

TO ALL WHOM IT MAY CONCERN:

Be it known that I, HARMAN A. M. HARRIS, of the city and county of Philadelphia, in the State of Pennsylvania, have invented certain new and useful Improvements in Pumps, of which the following is a full, clear, and exact description, reference being had to the accompanying drawings, which make part of this specification, and in which—

Figure 1 represents a vertical central section through my improved pump.

Figure 2, a front view of the pump-rod.

Figure 3, a view of the lower piston-head, seen from within.

Figure 4, a similar view of the upper piston-head.

Figure 5, a plan or top view of the same.

Figure 6, a view of the bottom of the lower piston-head.

Figure 7, a vertical section through the piston at the lines $x x$ of figs. 3 and 4; and

Figure 8, a similar section through the same, at the line $y y$ of fig. 4.

It is the object of my invention to render a double-acting pump both economical in construction and efficient in operation; and to this end my invention consists—

First. In a double-acting piston, through which both ends of a double-acting pump-chamber are filled and discharged at each reciprocation of the piston.

Second. In so combining a double-acting piston with a tubular piston-rod and air-chamber as to produce a continuous discharge.

Third. In combining a double-acting piston, reciprocating in a cylinder, with a tubular piston-rod, working through the cylinder, and serving both for an induction and an eduction pipe.

To any proper support, A, for example, I attach, by brackets a and a' , a pump-cylinder, B, closed at the bottom by a tight screw-cap, b, and at the top by a similar cap, b', each of which has a stuffing-box, C, in the centre, to support and guide a tubular piston-rod, D, the upper end d of which, in its reciprocal movement, rises into an air-chamber, E, secured to the upper cap b' of the pump-cylinder B, while the lower end d' of the piston-rod D reciprocates in the reservoir or well. The water is discharged through a pipe, F, located at the base of the air-chamber E. A double-acting piston, G, to the upper end of which the tubular piston-rod D is attached, is reciprocated in the cylinder B by a bifurcated pump-rod H, attached at its top to a bell-crank lever, J, which may be operated by hand, with a handle inserted in the socket K, or by any suitable connection with other power. The bifurcated ends of the pump-rod H are swivelled to a cross-head, L, that has a centre opening, l, in which the tubular piston-rod D is secured by a set-screw, l'. The piston-head being thus operated by an attachment below the pump-cylinder, obviates the necessity of using a third stuffing-box in the air-chamber when situated centrally over the cylinder, and the long arms of the pump-rod render the reciprocations of the piston smooth and easy.

The piston G is constructed in three parts, as follows: First, the barrel M has a plug, m^2 , at the bottom, which is drilled with two openings m and m^1 , and furnished with valve-seats for the ball-valves 1 and 2, as shown in fig. 1, in section, while the valve-seats are shown in a plan view in fig. 3. These openings m and m^1 have the partition between them cut away at the bottom, (as shown in figs. 1, 6, 7, and 8, at 2,) so as to let the water entering the piston pass freely through either valve when open. Openings p and p' are also made through the plug m^2 in the barrel, to permit a free passage of the water between the part of the pump-chamber above the piston-head and the part of the chamber below the head, when the proper valve to control this communication is intermittently closed and opened.

The second part of my piston is shown in figs. 1, 7, and 8, and consists of a disk, d^2 , having the openings p and p' , above described, continued through it. To this disk the lower part d^1 of the tubular piston-rod is firmly attached, and the disk is let into the lower end of the barrel M, flush with its edge, where it is secured by screws s and s' , that pass into the third part of my piston, which is shown in figs. 4, 5, 7, and 8, and consists of a cylindrical block, O, having a longitudinal gateway, P, cut through it to admit a flow of water through it from the barrel M to the upper end of the pump-cylinder. Opposite to the gate P the plug O is cut away on its lower side, as at R, to permit the water to pass from the barrel through a horizontal drilled opening, S, that is furnished with a valve-seat, $r r'$, on each side, to be alternately closed and opened by a ball-valve, 3, that is

free to move from one seat to the other, as influenced by the up-and-down movement of the piston. To the plug O the upper portion d of the tubular piston-rod is firmly secured, and the plug is inserted in the barrel until its top is flush with the edge of the barrel, and it is secured in position by the screws s and s' , fig. 8, which hold the two parts securely together.

The piston, thus constructed, is inserted in the pump-cylinder, the caps of which are put in place, and the pump-rod properly attached and secured, when the pump is ready for operation.

On raising the pump-handle, the piston rises in the cylinder, the valve 1 opens, and valve 2 is closed, while the valve 3 is closed on the side R. The water now ascends in the piston-rod d^1 , and through the valve 1, and overflows from chamber m , through openings m^2 , into the lower end of the cylinder, through the openings $p p'$. At the same time the water in the upper end of the cylinder is forced through the side opening P in the piston-head, through the now open valve r' on that side, the pressure keeping valve 2 closed, and up through the piston-rod d into the air-chamber, and thence out at the spout F. On the down stroke of the piston the valve 1 closes, owing to the backward pressure through the openings $p p'$, and 2 opens, and valve 3 shifts to its seat r , opposite the opening P, when the water flows through the lower part d^1 of the piston-rod, through the now open valve 2 and side opening P, into the top of the cylinder, while the water in the lower part of the cylinder is forced through the openings m^2 and the now open valve r , into the air-chamber, through the upper part d of the piston-rod. Thus, during the reciprocation of the piston, a constant stream of water will flow through the piston-rod, and be discharged from the pipe F, which renders my pump double acting and perfectly effective.

The red arrows show the current on the down stroke of the pump, and the blue arrows the current on the up stroke.

What I claim as my invention, and desire to secure by Letters Patent, is—

1. A double-acting piston, constructed substantially in the manner described, whereby I produce a continuous current through the piston by its reciprocation.
2. The combination of the double-acting piston, constructed substantially in the manner described, with the tubular piston-rod, the pump-cylinder, and air-chamber, for the purposes set forth.
3. The combination, substantially in the manner described, of the double-acting piston-head with the tubular piston-rods and cylinder, for the purpose set forth.

In testimony whereof I have hereunto subscribed my name.

HARMAN A. M. HARRIS.
